UNITED STATES PATENT OFFICE.

ISAAC F. WILLIAMS, OF BRISTOL, ASSIGNOR TO NATIONAL RUBBER COMPANY,
OF PROVIDENCE, RHODE ISLAND.

DESIGN FOR RUBBER OVERSHOES.

Specification forming part of Design No. 5,095, dated July 4, 1871.

To all whom it may concern:

Be it known that I, ISAAC F. WILLIAMS, of the city and county of Bristol and State of Rhode Island, have originated a new and artistic ornamental Design for Rubber Overshoes; and I do hereby declare that the following specification, taken in connection with the drawing furnished, and forming a part of the same, is a clear, true, and exact description thereof.

Figure 1 represents, in side view, a shoe exhibiting my design. Fig. 2 is a top view of the same.

Referring to the drawing, A is an edge-strip of rubber raised from the main surface and surrounding the ankle-opening of the shoe. B is an ornamental raised strip extending in a curved line downward from the under side of the strip A on the quarter to a point slightly in advance of the heel and above the arch; thence in a graceful curve upward and forward to the instep, where it forms a point crossing the instep and describing corresponding curves on the opposite side of the shoe. C is another ornamental line-strip of

a similar character, extending from the under side of the line B, at a point somewhat in advance of the heel and above the arch. This line extends on an easy graceful curve downward and forward to near the toe of the shoe; thence upward and slightly curved toward the rear of the shoe on the vamp. D is a ribbed vamp. The rib-lines extend from the line B to C, from their junction to the instep, and from that point forward extend across the vamp from the line C on one side of the shoe to the corresponding line on the opposite side.

Having thus described my said design, I claim—

The design for the ornamentation of rubber shoes, consisting of the ribbed vamp D, surrounded by the raised ornamental strips C and B, the latter extending to the quarters, substantially as described and shown.

ISAAC F. WILLIAMS.
